LINGERIE HANGER OR THE LIKE

Raymond E. Rutherford, Mount Vernon, Ill.

Application September 15, 1955, Serial No. 37,950

Term of patent 7 years

(Cl. D80—8.5)

I claim:

The ornamental design for a lingerie hanger or the like, as shown.
